PAPER FEEDING MECHANISM

Franklin E. Curtis, Willoughby, Ohio, assignor to
Addressograph-Multigraph Corporation, Cleve-
land, Ohio, a corporation of Delaware

Original application June 10, 1937, Serial No.
147,507. Divided and this application Novem-
ber 13, 1937, Serial No. 174,394

10 Claims. (Cl. 271—22)

This invention relates to paper feeding mechanism, and is especially concerned with an improved paper-feeding mechanism for use in connection with printing or duplicating machines. The present invention is a division of my co-pending application, Serial No. 147,507, filed June 10, 1937, and assigned to the assignee of the present invention, Addressograph-Multigraph Corporation.

10 The general object of the present invention is to provide an improved and compact paper-feeding mechanism, which is especially arranged for use in printing or duplicating machines of the type adapted for general office use. One of the 15 more specific objects of the invention is to provide a feeding mechanism which is simple in operation and which will require the minimum amount of attendance by the operator, to the end that comparatively unskilled operators may successfully operate the mechanism over continuous 20 periods of time.

25 A further object of the present invention is the provision of a simple and compact sheet feeding mechanism, which may be incorporated in a rotary printing machine, and which will feed sheets, one at a time, from the top of the stack, in timed relation to the printing member, regardless of the thickness of the sheets of the 30 stack, without requiring the making of complicated adjustments, or the use of complicated mechanisms, and thus enable comparatively unskilled operators to successfully operate the mechanism.

35 Other objects of this invention will become apparent from the following description, reference being had to the accompanying drawings, in which there is illustrated a preferred embodiment of the invention. The essential features of the invention will be summarized in the claims.

40 In the drawings, Fig. 1 is a horizontal section taken through a printing machine in which my improved paper-feeding mechanism is incorporated, the plane of the section being taken along the line 1—1 of Fig. 2; Figs. 2 and 3 are vertical sections, the planes of the sections being indicated by the lines 2—2 and 3—3 respectively, on Fig. 1; Fig. 4 is a sectional detail, the plane of the section being indicated by the offset lines 4—4 on Fig. 2; Fig. 5 is a fragmentary vertical section, as indicated by the lines 5—5 on Fig. 2.

45 Referring again to the drawings, it will be seen that I have illustrated my improved paper-feeding mechanism in connection with a printing machine, having a printing roller 10 provided

5 with a printing plate 17. However, in place of the plate 17 I may use the usual offset printing blanket, to which the image is applied in the manner generally well known in the planographic printing art.

As shown, the printing drum 10 is secured to a shaft 11, which is journaled in a pair of spaced end frame plates 12 and 13. The frame plates are tied together by cross-frame members generally indicated at 14. Cooperating with the printing drum 10 is a platen roll 15, which may likewise be journaled in the frame plates 12 and 13. The printing drum 10 may be driven in any well-known manner, such as, for instance, by a motor, through gears which mesh with a gear 18, 15 secured as shown in Fig. 1, to either the drum 10 or its supporting shaft 11, as shown in Fig. 1.

As heretofore mentioned, my improved sheet-feeding mechanism is adapted to feed the uppermost sheet of paper from a stack. As shown in the drawings, the paper stack is preferably supported by a table 20, which is slidably mounted for vertical movement in the frame members 12 and 13 in the printing machine. The arrangement is such that the table 20 is raised at periodic 25 intervals to maintain the uppermost sheet in the stack in horizontal plane, passing substantially within the bite of the platen roll 15 and the printing roll 10.

30 As illustrated in Fig. 1, the paper table comprises a horizontal plate-like member having side flanges 21, each of which is provided with a pair of rollers 22. These rollers project outwardly from the sides of the table 20, and engage the walls of slotted openings 23, formed in the respective frame plates 12 and 13, thus guiding the table for vertical movement.

35 The table 20 is periodically raised by suitable mechanism, which is operated by the printing roll shaft 11, and when raised, is maintained in 40 its raised position by suitable detent mechanism.

45 In the raising mechanism illustrated herein, the table 20 is provided at either side with a downwardly depending plate 24, provided with a rack-like formation 25. These racks are engaged by pinions 26, drivingly secured to a shaft 27 journaled in the frame members 12 and 13. Drivingly secured to the shaft 27, as shown in Fig. 2, is a ratchet wheel 28, which is periodically engaged by a pawl formation 29 of a lever 30. 50 This lever is pivotally mounted as at 31 on one arm 34 of a bail 32, which is pivoted to the frame intermediate the ends of its arms as at 33. The outer end of the arm 34 is provided with a roller 43, which is intermittently engaged by a cam 48. 55

secured to the printing drum 10, thus raising and lowering the lever 30 to advance the ratchet wheel 28, step by step.

Mechanism is provided, whereby the pawl formation 29 is maintained out of engagement with the ratchet wheel 28 until a predetermined number of sheets, or more specifically, until the stack of sheets has been reduced by a predetermined thickness. As shown in the drawings, a lever 45 is rotatably journalled on the ratchet wheel shaft 27. One end of this lever is arranged to engage a pin 46, secured to the lower end of a lever 30, and when in engagement therewith, retains the pawl formation 29 out of engagement with the ratchet 28.

As the sheets are fed from the stack W on the table 20 they are withdrawn from beneath the overhanging lips 51 of a series of fingers, or hold-down members 50. These fingers are mounted for 20 vertical sliding movement on a frame member 55 and are resiliently drawn downwardly toward the table by springs 52a. One of the fingers 50, such as, for instance, the finger 50a in Fig. 5, is provided at its lowermost end with a pin 54, which is 25 embraced by the slotted end of a lever 52, pivoted as at 53, to the frame plate 55. The lever 52 extends outwardly through an opening 56 in the frame member 13, and is provided at its outer end with a pin 57, which is engaged by the forked end 30 58 of the lever 45, heretofore described, thus controlling the movement of this lever, as well as the effective operation of the table feed mechanism by the height of the sheets in the stack.

When a sufficient number of sheets have been 35 withdrawn from the table to rock the lever 45 at a distance permitting the pin 46 to disengage the forward end of the lever 45, the pawl formation 29 advances the ratchet 28, thus raising the table. This raising movement of the table also raises the 40 fingers, thereby resetting the lever arm 45.

The paper feed table is maintained in its raised position by a detent pawl 60, which is pivoted as at 61 to a frame member, and is maintained in engagement with the ratchet wheel 28 by a spring 45 62, interposed between the lever 30 and the pawl 60, thus moving both the detent pawl 60 and the driving pawl member 29 toward the ratchet 28.

When it is desired to lower the table to replenish the supply of sheets, the operator pushes inwardly on a knob 65 (Figs. 1 and 4). This knob is slidable axially on the outermost end of the shaft 27, which projects through the frame member 13 and the cover plate 13a. When moved toward the machine the inner end of the knob hub 55 engages a bevelled nose 66 of the pawl 60, thus disengaging the detent pawl from the ratchet, permitting the table to drop under the control of the knob, which is drivingly secured to the shaft by the usual pin and slot connection. After a 60 block of sheets has been placed on the table, the rotation of the knob in a clockwise direction raises the table, to bring the topmost sheet into feeding position, with a consequent slight raising of the fingers 50.

65 The sheet feeding mechanism with which this invention is especially concerned separates the top sheet from the stack on the table before such sheet is fed into the bite of the printing roll. This separating movement of the sheet withdraws it from beneath the lips 51, and is accomplished by a feed roller 70. This roller is rotated first in one direction and then in the other, and is bodily reciprocated into and out of contact with the sheets.

As shown in the drawings, the feed roller 70 is 75 provided with a rubber sheath or covering 66a,

and is drivingly secured to a shaft 71, journalled in the arms 34 of the bail 32, heretofore described. The feed roller 70 is rotated by a reciprocating rack 73 (Fig. 2), which engages a pinion 71a on the shaft 71. This rack is formed on the under-surface of a link 74, pivotally attached as at 75, to a lever 76, which is pivotally mounted on a shaft or stud 77. To maintain the shifting rack in engagement with its pinion I provide a guide shown as comprising a sleeve 72 on the shaft 71, 10 having upwardly extending flange which carries ears 72a extending across the top of the link 74 and then downward on the far side thereof.

The lever 76 is swung about its pivot, in timed relationship with the rotation of the printing 15 drum 10, by a pair of cams 78 and 79, which are secured to the printing roll 10. A cam groove 80 is formed between these two cams and receives a roller 81, carried by the lever 76. Thus, as the cams 78 and 79 swing the lever 76, the feed roll 70 20 is rotated first in one direction and then in the other, as indicated by the arrows on Fig. 1.

As shown, the exterior cam 78 is segmental. However, the frictional contact between the roll 70 and the uppermost sheet in the stack maintains 25 the feed roll in contact with the cam 78 during the major portion of its rotation. However, a stop 82 is provided to prevent the roller 81 from moving out of the path of the cams 78 or 79.

As indicated, the feed roll 70 rotates in a clockwise direction, and to withdraw a sheet from beneath the lips 51 and carry it rearwardly, and due to a stop bar 83, which engages such sheet at the rear of the roll, the sheet is buckled, as indicated at W1, separating the top sheets from the remaining sheets in the stack. When the top sheet has been separated, the cam and rack mechanism operates to rotate the feed roll 70 in a counter-clockwise direction at a comparatively high rate of speed, and the stop-bar is simultaneously raised 35 out of contact with the sheet, as hereinafter more fully described. The raising of the stop-bar in a counter-clockwise movement of the feed roller results in the sheets being rapidly progressed into the bite of the printing couple. The feed roll is 40 then raised clear of the sheet, as hereinafter described, permitting the printing couple to complete the withdrawal of the sheet.

The paper stop-bar 83, which is used whenever average or light-weight sheets are being fed, is a 50 yoke-like member having its bar portion 84 encased in a rubber or similar gripping material 85. This stop-bar is pivotally secured to pins 86, carried by the frame plates 12 and 13, and is rocked up and down, about such shaft, by a cam 86a 55 (Fig. 2), which is secured to the printing drum shaft 11. This cam 86a coacts with a roller 87, carried by one end of a bell crank 88, pivoted as at 89, to the frame member 13. The outer end of this bell crank is pivotally connected to the stop 60 bar 83, by a link 90.

When comparatively heavy sheets are being fed, it requires a considerable distance for the formation of the separating buckle W1. The stop bar 83 is then moved up and held out of contact with the 65 sheets, and the sheets are buckled against a back stop which may be the rear paper guide. As shown in the drawings, the stop bar 83 is held out of engagement with the sheet by a latch or hook 91, which is pivotally mounted to the frame member 12, as for instance, on one of the cross-frame bars 14. The hook 91 is arranged to be swung from an idle position, in contact with a stop pin 92, as shown in full lines in Fig. 2, to the dotted line position shown in that figure, in which latter 70 75

position the hook engages a pin 93, which may be the extension of the pivot pin between the link 90 and the bell crank 88, thus maintaining the stop-bar out of engagement with the sheets W. The rear paper guide may comprise a plate-like member 95 extending vertically upward at the rear end of the stacked sheets, and adjustably positioned in contact with the stack by an adjusting screw or nut 96.

10 Figs. 1 and 3 show at 100 a suitable stop bar to engage the topmost sheet and indicate that the table has been elevated to the proper position after the stack of sheets has been replenished. This bar is a convenience, but may be omitted if desired. It is shown as a ball having upward arms encircling the pins 86. When the rear paper guide 95 is used as the back stop, for buckling heavy sheets, the ball 100 is turned up to idle position.

20 As heretofore mentioned, the feed roll 10 is periodically moved up and down. The feed roll is raised out of contact with the sheet immediately after its counter-clockwise rotation, at which time the sheet has been fed to and gripped by the printing rolls 10 and 15. The sheet is then further withdrawn from the stack, solely by the operation and contact of the sheets with such printing rolls. This movement of the feed roll toward and from the stack W is accomplished 25 by the mechanism which was heretofore described in connection with the table raising mechanism, and includes the rollers 43, the ball 32 and the cam 48. Inasmuch as the feed roll is journaled between the arms 34 of the ball, the swinging movement imparted thereto by the cam to raise the paper feed table serves to raise and lower the feed roll.

30 When, for any reason, it is desired to stop the paper feed, the operator merely trips the lever 40 120, Fig. 2, to release it from the cam 121, which thereupon is swung by the spring 122 to engage the roller 43 and raise the feed roller out of engagement with the paper. To enable the tripping of the lever 120 to be very readily effected manually, I extend a tongue 125 from the side of the lever outwardly through a slotted opening in the machine casing. Engagement of this tongue by the operator's finger will release the cam and stop the feed. This same movement by 45 raising the feed roller carries the raising pawl 29 upwardly out of operating position, and thus stops any elevation of the paper table.

40 The feeding mechanism is also automatically thrown out of action whenever the table is raised 50 to a predetermined position, so that the feed will be stopped just before the final sheet or sheets have been fed. This is effected by the upper guide roll 22 of the paper table engaging the lower end of the latch lever 120. The 55 time of this engagement may be accurately selected by adjusting the position of the roller 22 on the raising paper frame, as, for instance, by providing an eccentric bushing between the bore of this roller and the supporting pin on the raising frame.

60 Whenever it is desired to restore the paper feed to active position, this is readily accomplished by swinging down the hand lever 130, which is rigidly connected with the cam 121. When the cam 65 is swung down to idle position, the lever extends vertically; then, to restore the paper feed, the lever is merely turned to horizontal position, thus turning the cam back about one-quarter turn, where it is engaged by the latch lever 120.

70 The connection between the lever 130 and the

cam may be effected by pinning both members tight to the shaft 11, and making all the other parts on the shaft loose thereon, or by leaving the lever and cam loose of the shaft and connecting them by a sleeve loosely surrounding the 5 shaft.

I claim:

1. In a paper feed mechanism, the combination of a means for supporting a stack of sheets, a roller adapted to engage the endmost sheet, a carriage in which said roller is rotatably mounted, a guideway on said carriage, a rack geared to the roller and mounted in said guideway, and means pivotally connected with said rack to reciprocate the rack to rotate the roller first in one direction 10 and then in the other direction, a rotary cam to actuate said lever, and means to move said carriage and rack and roller toward and away from the stack.

2. In a paper feed mechanism, the combination 20 of a means for supporting a pile of sheets, a roller adapted to engage the topmost sheet, a carriage in which said roller is rotatably mounted, said carriage being pivotally mounted to move the roller toward or away from the top sheet of the 25 pile, a guideway on said carriage, a rack geared to the roller and mounted in said guideway, a lever pivotally connected with said rack to reciprocate the rack to rotate the roller first in one direction and then in the other direction, a rotary 30 cam to actuate said lever, a second rotary cam to swing said mounting about its pivot, and a common operating means for both rotary cams.

3. The combination of a paper table, a back 35 stop for a pile of sheets on the table, a reversible feed roller adapted to engage the topmost sheet of the pile, a stop bar between the feed roller and back stop, movable independent of the latter means for moving the stop bar into engagement with the topmost sheet and while in such 40 engagement rotating the feed roller in the direction to buckle the sheet between it and the stop bar, means for thereafter raising and lowering the feed roller and while it is raised reversing its direction, and means for raising the stop bar, 45 so that the lowered and reversed roller may grip and feed the sheet from the stack.

4. The combination of a paper table, a back 50 stop for a pile of sheets on the table, a reversible feed roller adapted to engage the topmost sheet of the pile, a movable stop bar between the feed roller and back stop, means for moving the stop bar into engagement with the topmost sheet and while in such engagement moving the feed roller to buckle the sheet between it and the stop bar, 55 means for thereafter operating the feed roller in a reverse direction and raising the stop bar to feed the gripped sheet, and means for holding the stop bar idle while the back stop is effective, to enable the feed roller to buckle the sheet 60 against the back stop.

5. In a paper feed mechanism, the combination 65 of means for supporting a pile of sheets, a feed roller adapted to engage the endmost sheet, mechanism to turn the roller first in one direction to buckle such endmost sheet, and then in the opposite direction to feed the buckled sheet, and means for automatically moving the feed roller bodily for each sheet fed to cause the roller to clear the sheet after the feeding movement of the sheet 70 has started, and means for automatically moving the feed roller to idle position when the supply of paper is nearly exhausted.

6. In a paper feed mechanism, the combination 75 of means for supporting a pile of sheets, a feed

- 5 roller adapted to engage the endmost sheet, mechanism to turn the roller first in one direction to buckle such endmost sheet, and then in the opposite direction to feed the buckled sheet, and means for automatically moving the feed roller bodily for each sheet fed to cause the roller to clear the sheet after the feeding movement of the sheet has started, and manual means for moving the feed roller to idle position.
- 10 7. In a paper feed mechanism combination, means for supporting a pile of sheets, a feed roller adapted to engage the topmost sheet, mechanism to turn the roller first in one direction to buckle such topmost sheet, and then in the opposite direction to feed the buckled sheet, a cam operating for each sheet fed for moving the feed roller bodily to cause it to clear the sheet after the feeding movement of the sheet has started, a normally idle cam adapted to raise the feed roller from the top of the pile of sheets, and means for releasing the last-mentioned cam and for moving it when released to render the feed roll idle.
- 15 8. In a paper feeding mechanism, the combination of a horizontally extending table to support a stack of sheets, one above the other, a carriage pivotally mounted above said table to swing up and down toward and away from the topmost sheet in the stack, a feed roll journaled in said carriage for contact with a sheet when the carriage is swung toward the stack, a gear drivingly secured to said roll, a rack mounted for reciprocation in said carriage and operatively connected to drive said gear first in one direction and then in another, a rotary drive shaft, a cam mounted thereon, a pivoted lever operated by said cam and pivotally connected to recipro-

cate said rack, a second rotary cam on said shaft arranged and adapted to rock said carriage about its pivots, a stop bar pivotally mounted to move into and out of contact with the topmost sheet in the stack, a third cam on said shaft to operate said stop bar, said cams being arranged and adapted to cause the stop bar and roll to be in contact with the topmost sheet of the stack and to rotate the roll to move such sheet toward the stop bar, thereby causing the sheet to buckle and subsequently and simultaneously reverse the direction of rotation of the roll and raise the stop bar to eject the sheet from the stack, and thereafter raise the roll and reverse its direction of rotation prior to the bringing of the roll into contact with the next sheet.

9. The combination of a paper table, a back stop for a pile of sheets on the table, a device for buckling the top sheet on the pile, a movable stop bar between the buckling device and the back stop, means for moving the stop bar into engagement with the topmost sheet, and means for holding the stop bar idle when desired whereby the sheet may be buckled either against the stop bar or the back stop.

10. In a paper feed mechanism, the combination of means for supporting a stack of sheets, a pivoted bail, a roller adapted to engage the endmost sheet and mounted on a shaft carried by said bail, a pinion on the shaft, a rack meshing with the pinion, a sleeve surrounding the shaft and carrying a guide for the rack, means for reciprocating said rack and turning the feed roller in one direction and then in the other, means for swinging the bail about its pivotal axis to change the presentation of the roller to the paper.

FRANKLIN E. CURTIS.
